UNITED STATES PATENT OFFICE.

MAURICE L. AKERS AND ARTHUR D. SEIBERT, OF PENDLETON, OREGON.

CUTTING-TOOL.

1,371,660.

Specification of Letters Patent. Patented Mar. 15, 1921.

Application filed April 3, 1920. Serial No. 371,079.

To all whom it may concern:

Be it known that we, MAURICE L. AKERS and ARTHUR D. SEIBERT, citizens of the United States, residing at Pendleton, in the 5 county of Umatilla and State of Oregon, have invented certain new and useful Improvements in Cutting-Tools, of which the following is a specification, reference being had to the accompanying drawings.

10 This invention relates to improved cutting tools, and an object is to provide a device of this kind especially adapted for turning up worn bearings for crank shafts, such as used on automobiles, gas tractors, trucks and 15 the like.

A further object involves the provision of a tool which is simple, efficient and practical in construction, capable of being cheaply manufactured, and sold at a reasonable 20 profit.

Another object involves the provision of a tool comprising a frame or body having means adjacent which the work is disposed, in combination with a slide mounted in 25 guides of the frame or body, with means for adjusting the slide, whereby a cutting member may be adjusted toward and from the work, so that the work can be cut to any suitable size or diameter, and so that any 30 suitable amount of material may be moved from the crank shaft or other work operated upon.

While the design and construction at present illustrated and set forth is deemed 35 preferable, it is obvious that as a result of a reduction of the invention to a more practical form for commercial purposes, the invention may be susceptible to changes, and the right to these changes is claimed, provided they are comprehended within the 40 scope of what is claimed.

The invention comprises further features and combination of parts, as will be herein-after set forth, shown in the drawings and 45 claimed.

In the drawings:

Figure 1 is a view in side elevation of the improved tool constructed in accordance with the invention;

50 Fig. 2 is a plan view of the same;

Fig. 3 is a longitudinal sectional view on line 3—3 of Fig. 2; and

Fig. 4 is a cross sectional view on line 4—4 of Fig. 3, showing part of the means

for clamping the cutting tool proper in position, in full lines and part in dotted lines.

Referring more especially to the drawings, 1 designates a frame or body member which may be any suitable shape and size, preferably elongated as shown, and may be 60 made of any suitable material, preferably cast iron or steel, constructed in one piece as shown. This body has an upstanding portion 2 which is at right angles to the face 3 of the body. The body or frame is provided with an elongated slot 4, and guided in rabbets 5^a of this slot is a slide block or cutting tool holder 5. Passing upwardly through the block 5 is a cap screw or bolt 6. This cap screw or bolt 6 passes through 70 clamping plate 7 and is threaded into a tapped hole in the block. The forward upward portion of the slide block has an angle recess or rabbet 5^b in which a suitable cutting tool or knife proper 8 is secured. A 75 plate 9 is mounted upon the upper face of the slide block 5 and has one end overlying the cutting tool, in order to clamp the tool in the recess 5^b. The plate 9 has a downwardly extending lug 9^a which fits into a 80 cavity 9^b in the upper part of the slide block, to assist in holding the plate 9 in position. The plate 9 is held in clamping relation to the slide block and the cutting tool proper 8 by means of a cap screw or 85 bolt 10, which extends from below upwardly through the slide block 5 into a threaded opening 9^c of the plate 9. The cap screw or bolt 10 at its medial portion has a shoulder 11, which co-operates and clamps with 90 the under face of the slide block, in conjunction with the upper threaded end of the cap screw or bolt so as to clamp the clamping plate 9 in position and against the cutting tool proper. However, it is to be noted that 95 this cap screw or bolt does not clamp against the clamping plate 7, as the tension and the position of the slide block is governed entirely by the cap screw 6.

The upstanding portion 2 of the body is 100 provided with an angular recess or cavity comprising a pair of faces *a*, *a*. These faces are formed on inclined planes extending at 45° angles from the upper face or plane 3 of the body. However, the faces *a*, *a* are 105 constructed at right angles to each other, as shown. These faces may be tempered, or the faces may be constructed by providing

insert plates of tempered steel, and connected to the upstanding portion 2 in any suitable manner not shown. The upper end of the portion 2 is provided with an opening 5 13, rectangular in cross section for the reception of the shank 14^a of the work holding finger 14. The work holding finger 14 extends at right angles to the finger 14^a and depends in a direction toward the work to be 10 disposed adjacent the right angle faces *a*, *a*, thereby coöperating with said faces, to assist in guiding the work during its rotation and at the time it is being turned up. The shank 14 of the work holding finger fits the opening 13 closely. The shank 14^a of the work holding finger has a reduced extension 14^b, which is threaded, and is adapted to receive a threaded nut 15. This nut comprises a flange and a sleeve. 15

20 By means of this nut 15, the work holding finger is held in position. Also rising upwardly from the body or frame 1 is an upright standard 16, which is cast upon the body of frame 1 and is provided with a 25 tapped opening 16^a, for the reception of a threaded screw 17, one end of which is swivelly connected to the slide block as at 17^a in any suitable manner. A graduated sleeve 18 is suitably connected to the upright 30 or standard 16, and is provided with graduations 18^a. This graduated sleeve 18 extends in a direction from the block 5, and telescopically enters a sleeve 19 which is carried in any suitable manner by the hand 35 wheel 21 having a handle 22. This hand wheel 21 is suitably connected to the screw 17 preferably integrally therewith, though not necessarily, and it is obvious that by adjusting the screw in one direction or the 40 other, the slide block may be moved toward and from the work to be turned up. The sleeve 19 on its marginal beveled edge is provided with a series of graduations 20, which, by the rotating of the hand lever 21 45 are adapted to coöperate with the graduations 18^a, for gaging the depth of the cutting tool proper 8. In other words, when rotating the hand wheel, the slide block can be moved toward the work and the depth of 50 the cutting tool proper 8 gaged according to the coöperation of the graduations 18^a and 20 of the two telescoping sleeves 18 and 19.

In the operation of the device, the work holding finger 14 is first removed by removing 55 the nut 15 and sliding the finger out of the opening 14^a. The body or frame may then be adjusted, and the work or crank shaft to be turned up is then disposed in the cavity or recess of the upstanding part 2. 60 The slide block is then adjusted or moved back so that the tool proper 8 can be placed in the recess 5^b and clamped. However, before adjusting the block toward the upstanding part 2, the work or crank shaft to 65 be turned up is first placed in the angular

cavity of the upstanding part 2 and the work holding finger replaced and the nut 15 turned home. The work guiding finger 14 is positioned relatively close to the work or shaft to be turned up as indicated by the character *b*, after which the sliding block is adjusted toward the work so that the cutting tool proper may be in a position to act upon the work, its depth being governed by the adjustment of the hand wheel. 75

Should it be desired to use the tool in connection with a lathe, the elongated shank portion 23 of the body is rested or supported on the ways (not shown) of the lathe after which the lathe is operated slowly, 80 the work to be turned up being rotated at the same time, in which case the cutting tool proper will act upon the work, and turn it up as may be desired.

From the foregoing it is to be noted that 85 the present invention involves various advantages over the old method. For instance, the present device is simple in construction, and furthermore the tool may be applied in position with great ease. Furthermore, 90 the cutting tool, mounted as it is, requires no vertical adjustments as it is always in correct position. When the device is used in connection with a lathe it is in a position that insures the cuttings to fall away from 95 the work and are not carried around as is apt to occur with other tools now in use which operate in reverse positions. Furthermore, the tool operates in a position leaving the work visible at all times, making it possible 100 for the operator to watch the progress of the work, which is very important, and is one of the main features or advantages of the device. However, the tool may be operated by hand, 105 for instance, by holding the work or crank shaft to be turned up in a vise, and applying the tool or device to the work in the manner above set forth, and after which the tool or device may be swung around the work by hand instead of the tool or device 110 remaining stationary and the shaft or work to be turned up rotated as would be the case where the tool is operated in connection with a lathe.

The cap screw 10 operatively engaging the 115 slot 4 constitutes additional means for guiding the slot block when adjusted.

The invention having been set forth, what is claimed as new and useful is:—

1. In a tool of the kind set forth, a body 120 having an upstanding arm at one end provided with a work receiving cavity, working guiding means on said arm overlying the work, a cutting tool carrying element operatively guided on the body and carrying a 125 cutting tool to be positioned upon the work, means operatively mounted on the body and connected to the element for adjusting the same toward and from the work, means passing through the body and operatively 130

- connected to the element for holding the same in different adjusted positions, and acting as means to guide the element relatively to the body when adjusted, a clamping plate 5 on the element, means passing through the element and operatively connecting with the plate for clamping it in engagement with the cutting tool proper, said means passing through the element having means operatively passing through the body, for additionally guiding the element when adjusted. 2. In a tool of the kind set forth, a body provided with work receiving and guiding means at one end, a slide element operatively 15 guided upon the body, a cutting tool carried by the body, means for adjusting the element toward and from the work, clamping means for the cutting tool proper, means passing through the element and operatively 20 engaged with the clamping means for holding it clamped upon the cutting tool proper, said means passing through the element having means operatively passing through the body to assist in guiding the element when 25 adjusted.
3. In a cutting tool as set forth, a body, work receiving and guiding means at one end, a slide element operatively guided on the body and adapted to be adjusted toward 30 and from the work, a clamping member on the element overlying the clamping tool proper, means passing through the element and operatively engaged with the clamping member and coöperating with the element 35 for clamping the cutting tool proper independently of the body, said means passing through the element having means operatively engaging with the body to guide the element when adjusted. 4. In a tool as set forth, a body having a 40 guide slot, work receiving and guiding means on one end of the body, a slide ele-
- ment guided on the body, a cutting tool proper carried thereby, a clamping plate on the element overlying the cutting tool 45 proper, a device passing through the element and operatively engaged with the clamping plate, said device having a shoulder coöperating with one face of the element for drawing the clamping plate tightly in 50 position and operatively bearing upon the cutting tool proper to hold it in position, said device having means operatively engaging said slot to assist in guiding the element toward and from the work. 55
5. In a tool as set forth, a body having a guide slot, work receiving and guiding means on one end of the body, a slide element guided on the body, a cutting tool proper carried thereby, a clamping plate on 60 the element overlying the cutting tool proper, a device passing through the element and operatively engaged with the clamping plate, said device having a shoulder coöperating with one face of the element for drawing the clamping plate tightly in 65 position and operatively bearing upon the cutting tool proper to hold it in position, said device having means operatively engaging said slot to assist in guiding the 70 element toward and from the work, means operatively mounted on the body and being connected to the element for adjusting the same, and means carried by the element and operatively engaging said slot for holding 75 the element in different adjusted positions and acting as an additional guiding means for the element when being adjusted, said adjusting means including means for gaging the depth of the cutting tool proper. 80

In testimony whereof we hereunto affix our signatures.

MAURICE L. AKERS.
ARTHUR D. SEIBERT.
